UNITED STATES PATENT OFFICE

143,380

DESIGN FOR A COMPACT OR SIMILAR ARTICLE

Zachary Zemby, Los Angeles, Calif.

Application June 8, 1945, Serial No. 119,967

Term of patent 3½ years

(Cl. D86—10)

To all whom it may concern:

Be it known that I, Zachary Zemby, a citizen of the United States of America, residing in Los Angeles, county of Los Angeles, and State of California, have invented a new, original, and ornamental Design for a Compact or Similar Article, of which the following is a specification, reference being had to the accompanying drawing, forming part thereof.

Fig. 1 is a top perspective view of a compact or similar article showing my new design in closed position.

Fig. 2 is a bottom perspective view thereof.

Fig. 3 is a top perspective view showing the compact in open position.

I claim:

The ornamental design for a compact or similar article, substantially as shown.

ZACHARY ZEMBY.
